UNITED STATES PATENT OFFICE.

EDGEWORTH GREENE, OF MONTCLAIR, NEW JERSEY.

BOTTLE.

1,211,934.

Specification of Letters Patent.

Patented Jan. 9, 1917.

Application filed May 23, 1914. Serial No. 840,401. ~~PRINTED IN U.S.A.~~

To all whom it may concern:

Be it known that I, EDGEWORTH GREENE, a citizen of the United States, residing at Montclair, in the county of Essex and State 5 of New Jersey, have invented certain new and useful Improvements in Bottles, of which the following is a specification.

This invention relates to a non-refillable bottle, and its novelty consists in the construction and adaptation of the parts and in the application of the principles upon which the invention is based.

Many attempts have been made to make non-refillable bottles and have resulted in 15 the production of bottles which when once emptied could not be refilled merely by pouring a liquid back through the mouth of the bottle into the body. Yet, until my invention, so far as such bottles are known to 20 me, none were proof against methods of refilling which involved the immersion of the mouth of an empty bottle in a liquid attempted to be introduced therein and the creation of a pressure upon the surface of 25 the liquid greater than the pressure inside the bottle. The bottle hereinafter described of my invention cannot be refilled by any such method, nor indeed by any method known to me, and its function in this respect depends upon the fact that the closing 30 device or valve comprises two members, one heavier and one lighter than the liquid within the bottle which are made of such material that they will adhere and move together 35 when wet but will separate and cause the lighter member to float when both are immersed in the liquid provided, of course, the lighter member is uppermost.

In the drawings, Figure 1 is a longitudinal 40 sectional section of the upper part of a bottle provided with my invention, the parts being in the positions shown when the bottle is filled with liquid and sealed; Fig. 2 is a similar view of the same parts showing 45 their positions when the bottle is inverted in order to pour out its contents; Fig. 3 is a similar view of the same parts showing their positions when the bottle is placed on its side, such positions being the same irrespective of the amount of liquid in the 50 bottle; Fig. 4 is a similar view illustrating what occurs when an empty bottle is immersed, mouth downward, in a liquid in an attempt to refill it; Fig. 5 is a detailed top 55 plan view of the guard and guide, and Fig.

6 is a bottom plan view thereof; Fig. 7 is a bottom plan view of the terminal sleeve.

In the drawings, 10 represents a body of a bottle of which 11 is the shoulder and 12 is the neck. Placed upon the upper edge 60 of the neck is an annular gasket 13 made of cork or other suitable packing material, and placed above this is a member 14, which I call a terminal sleeve, and which is cylindrical in form, is provided with an external 65 shoulder indicated at 15 and terminates in a transverse disk 16 having a central aperture 17. It is open at the bottom. It is also provided with a series of internal longitudinal ribs 18 which are continued under 70 the disk 16. This sleeve serves as a housing for the parts hereinafter described and is secured to the neck of the bottle by a retaining casing 19 preferably made of metal and spun onto the neck of the bottle over 75 the usual bead indicated at 20 and around and above the shoulder 15 of such sleeve. Arranged above the gasket or packing 13 and fitting snugly within the sleeve 14 is a seat 21 in the form of a ring made of porcelain or other suitable material, and having a depending flange 22 passing downwardly inside of the gasket 13. Arranged above this seating ring and adapted to rest 80 thereon by gravity is a valve comprising 85 two members, namely, a lower member 23 of cork or similar material lighter than the liquid to be placed in the bottle, and which member is the valve proper, and an upper member 24 of porcelain or similar material 90 heavier than the liquid to be placed in the bottle and which is, in effect, a weight. The member 23 fits loosely within the ribs 18 of the sleeve 14 and the member 24 rests upon it by gravity. The member 24 is composed of two parts, namely, a lower cylindrical part 24^a and an upper frusto-conical part 24^b, although the two parts are made 95 integral.

It is essential to the operation of the device that the weight 24 of the lower member 23 of the valve should be made of such a material that their contacting surfaces shall adhere when wet by the liquid in the bottle. It is further essential that if the material 105 of which the ring 21 is composed is such that it also will adhere to the valve 23 when wet then the contacting surfaces shall be so proportioned that when the bottle is inverted the member 23 will adhere to the 110

weight 24 and not to the seating ring 21. Above the weight 24 and also arranged within the sleeve 14 there is provided a combined guard and guide 25 which is cylindrical in external form. It is closed at the top and open at the bottom and is provided internally with a frusto-conical recess similar in form to the contour of the upper part 24^b of the weight 24. Along such recess it is also provided with a series of ribs indicated at 26. The top of the guard and guide is provided with an annular recess 27 leaving a wall 28 at its outer edge. Placed above the sleeve 14 is a stopper 29 having an inwardly projecting cork member 30 and adapted to fit snugly within the aperture 17 in the sleeve. This stopper when in position presses down upon the guard and guide 25 and this in turn upon the weight and valve and consequently tends to close the mouth of the bottle tightly in transit or whenever it is desired to keep its contents sealed.

In use the bottle is first filled with the desired liquid. The described parts are then assembled as shown in Fig. 1 but without the stopper 30, and the retaining casing 19 is put in place, and the stopper 30 is then inserted. When it is desired to pour out the contents of the bottle the stopper 30 is removed and the bottle is inverted or tipped into the position shown in Fig. 2, the liquid presses upon the lower side of the cork valve 23 and creeps around into the space between it and the sleeve 14, that is between the ribs of the sleeve. As soon as the contacting surfaces between the valve 23 and the weight 24 are wet these members adhere, and even should the space surrounding them become filled with liquid there will be no tendency for these members to separate. Such space, however, does not readily entirely fill because as the liquid passes out of the bottle around the guard and guide the air enters the mouth of the bottle and creeps through the space between the ribs of the sleeve 14 and enters the body of the bottle thus replacing the liquid drawn therefrom. If the bottle is partly emptied and then placed in an upright position the weight 24 will fall by gravity upon the valve 23 and cause the latter to rest upon the seat 21 to close the opening into the bottle. If the bottle is placed on its side in the position shown in Fig. 3, the same result will take place because of the co-operating sloping sides of the weight 24 and the guard and guide 25, as the weight will always slide to a lowermost position and in such position will push the valve 23 against the seating ring 21 and effectually close the mouth of the bottle. If the bottle is completely emptied and its mouth is submerged in a body of liquid, as shown in Fig. 4, the guard and guide will drop to the position

shown in that figure and so will the weight 24, because it is heavier than the liquid, but as soon as liquid is introduced into the aperture 17 and passes around in the space between the ribs of the sleeve and on both sides of the valve members 23 and 24, the valve member 23 being lighter than the liquid will float and rise and seat itself against the surface of the ring 21, and if pressure should be put upon the surface of the liquid outside of the bottle to force the liquid upward into the bottle, the greater the pressure the tighter will be the closure and the further introduction of the liquid into the bottle will be entirely prevented. The wall 28 of the guard and guide 25 and the annular groove or recess 27 inside of the wall is a baffling device to prevent the introduction of a wire or tool through the opening 17 of the sleeve 14 down into the sleeve between the ribs 18 to possibly engage the weight 24 or the valve member 23 to hold the valve away from its seat and thus permit the introduction from above of liquid into the body of the bottle. While the possibility of an attempt at such manipulation of the valve is remote, this particular device has been provided to prevent it, which it does, because when such use of a wire or the like is attempted its end is caught in the recess 27 and against the wall 28 and it cannot be further forced downward into the sleeve.

What I claim is:

1. A non-refillable bottle comprising a reservoir provided with a separate valve-compartment having a discharge orifice; a valve-seat intermediate the orifice and the reservoir; a valve including a float; weighted-means, separate from the float and retained against escape from said valve-compartment, adapted and arranged to move the float in a direction away from the seat when the bottle containing the liquid is tilted from an upright into a pouring position and to move the float, in response to gravity, in a direction toward the seat when the bottle is returned from a pouring to a horizontal position, and when refilling with liquid is attempted while the bottle is in an inverted position communication through said seat is closed by the movement of said float, due to its flotation on the entering liquid, in a direction toward said seat; and further means for preventing adhesion, between the weighted-means and any adjacent surface of any element of the bottle, sufficient to prevent the closing of the valve when refilling with liquid is attempted.

2. A non-refillable bottle comprising a reservoir provided with a separate valve-compartment having a discharge orifice; a valve-seat intermediate the orifice and the reservoir; a valve including a float;

weighted-means, separate from the float and retained against escape from said valve-compartment, adapted and arranged to move the float in a direction away from the seat when the bottle containing the liquid is tilted from an upright into a pouring position, and to move the float, in response to gravity, in a direction toward the seat when the bottle is returned from a pouring to a horizontal position; and the configuration of the surfaces of the weighted-means as well as that of the adjacent surface of any element of the bottle being such that the adhesion between them is insufficient to prevent the closing of the valve when refilling with liquid is attempted.

3. A non-refillable bottle comprising a reservoir; an adjacent separate valve-compartment having a discharge orifice; a valve-seat intermediate the orifice and the reservoir; closing-means, including a float and weighted-means permanently retained against escape from said valve-compartment, for normally sealing communication through said valve-seat, said weighted-means including a weight movable with respect to the float; that part of said closing-means, adjacent the valve-seat and including the float, constituting a float-valve and the arrangement of the members of said closing-means being such that, when the bottle containing liquid is tilted from an upright to a pouring position, communication through said valve-seat is opened by the movement, in response to gravity, of an element of said closing-means which in turn effects movement of the float in a direction away from the seat; when the bottle is returned from a pouring to a horizontal position, communication through said seat is closed by the movement, in response to gravity, of an element of said closing-means which in turn effects movement of the float in a direction toward said valve-seat; and when refilling with liquid is attempted while the bottle is in an inverted position communication through said seat is closed by the movement of said float, due to its flotation on the entering liquid, in a direction toward said seat; and said closing-means also including further means for preventing adhesion, between the surface of the weight and an element of the bottle adjacent thereto, sufficient to interfere with the closing of communication through the valve-seat when refilling with liquid is attempted.

4. A non-refillable bottle comprising a reservoir; an adjacent separate valve-compartment having a discharge orifice; a valve-seat intermediate the orifice and the reservoir; closing-means, including a float and weighted-means permanently retained against escape from said valve-compartment, for normally sealing communication through said valve-seat, said weighted-means includ-

ing a weight movable with respect to the float; that part of said closing-means, adjacent the valve-seat and including the float, constituting a float-valve and the arrangement of the members of said closing-means being such that, when the bottle containing liquid is tilted from an upright to a pouring position, communication through said valve-seat is opened by the movement in response to gravity, of an element of said closing-means which in turn effects movement of the float in a direction away from the seat; and when the bottle is returned from a pouring to a horizontal position, communication through said seat is closed by the movement in response to gravity of an element of said closing-means which in turn effects movement of the float in a direction toward said valve-seat; and the configuration of the surface of the weight, as well as that of any surface of an element of the bottle adjacent thereto, being such that adhesion between them is insufficient to prevent the closing of communication through the valve-seat when refilling with liquid is attempted.

5. An attachment for rendering bottles non-refillable, including a valve-compartment, having a discharge orifice at one end and a valve-seat at the other, and containing a guard-member, the interior surface of which is of frusto-conical configuration, and a coöperating slidable weight-member having a corresponding frusto-conical configuration at one end and a cylindrical configuration at the other, the maximum diameter of said conical portion being equal to that of said cylindrical portion, and the configuration of the adjacent surfaces of said guard and said weight being such that the adhesion therebetween when wet will be insufficient to prevent the separation thereof in response to gravity.

6. An attachment for rendering bottles non-refillable, including a valve-compartment, having a discharge orifice at one end and a valve-seat at the other, and containing a guard-member, the interior surface of which is of frusto-conical configuration, and a coöperating slidable weight-member having a corresponding frusto-conical configuration at one end and a cylindrical configuration at the other, the maximum diameter of said conical portion being equal to that of said cylindrical portion, said cylindrical portion of said weight-member only being adapted to project from said guard-member when said weight-member is in its innermost position with respect thereto, the configuration of the adjacent surfaces of said guard and said weight being such that the adhesion therebetween when wet will be insufficient to prevent the separation thereof in response to gravity.

7. An attachment for rendering bottles non-refillable, including a valve-compartment

having a discharge orifice at one end and a valve-seat at the other and containing a guard-member the interior surface of which is of frusto-conical configuration, and a co-
5 operating slidable weight-member having a corresponding frusto-conical configuration at one end and a cylindrical configuration at the other, the weight-member being so proportioned that when at its innermost position
10 within said guard-member its cylindrical portion only will project therefrom and its center of gravity will be in such a relative position as to render said weight-member very sensitive to the influence of gravity in
15 its tendency to move away from the guard-member when the attachment is in a substantially horizontal position, and the configuration of the adjacent surfaces of said guard and said weight being such that the
20 adhesion therebetween when wet will be insufficient to prevent the separation thereof in response to gravity.

8. A non-refillable bottle, comprising a casing adapted to be secured to the neck of a
25 bottle and having a discharge orifice at one

end and a valve-seat at the other, a valve comprising two parts, one of which is a cork disk-valve positioned next to said valve-seat and adapted to contact with said valve-seat with one of its faces only, and a weight-
30 member having a frusto-conical configuration at its end adjacent said orifice and of cylindrical configuration at its other end, the maximum diameter of said conical portion being equal to that of said cylindrical portion, a guide for said weight-member also having a frusto-conical recess into which said weight-member is adapted to partially project, ribs interposed between said weight-member and said guide to prevent adhesion
35 therebetween, a baffle wall between said guide and said orifice, and a stopper for the casing adapted to hold the movable parts thereof stationary within said casing.

In testimony whereof I affix my signature
40 in presence of two witnesses.

EDGEWORTH GREENE.
